United States Patent Office

Des. 186,466
Patented Oct. 27, 1959

186,466

VENDING MACHINE

Waldo E. Bolen, Jr., Morris, Ill., and Lee A. Roehlke,
Fridley, Minn.

Application June 15, 1959, Serial No. 56,333

Term of patent 3½ years

(Cl. D52—3)

Fig. 1 is a perspective view of a vending machine embodying our new design;

Fig. 2 is a side elevational view thereof; and

Fig. 3 is a top plan view thereof.

The rear is substantially plain, and the side not shown is similar to the side shown.

We claim:

The ornamental design for a vending machine, substantially as shown and described.
